CLAIM

The ornamental design for a disposable air and water valve for an endoscope, as shown and described.

DESCRIPTION

FIG. 1 is a perspective view of a disposable air and water valve for an endoscope;

FIG. 2 is a side disassembled view of the disposable air and water valve for an endoscope;

FIG. 3 is a side view of a stem portion of the disposable air and water valve for an endoscope;

FIG. 4 is a top view of the spring stanchion portion of the disposable air and water valve for an endoscope; and,

FIG. 5 is a side assembled view of the disposable air and water valve for an endoscope.

The broken lines of the figures depict unclaimed portions of the disposable air and water valve for an endoscope.

1 Claim, 4 Drawing Sheets
